UNITED STATES PATENT OFFICE.

EBENEZER DANFORD AND CHARLES E. A. SAGLE, OF AURORA, ILLINOIS.

SMOKE-CONSUMER.

SPECIFICATION forming part of Letters Patent No. 417,412, dated December 17, 1889.

Application filed August 27, 1889. Serial No. 322,139. (No model.)

To all whom it may concern:

Be it known that we, EBENEZER DANFORD and CHARLES E. A. SAGLE, citizens of the United States, residing at Aurora, county of Kane, and State of Illinois, have invented 5 certain new and useful Improvements in Smoke-Consumers, of which the following is a full, clear, and exact description, that will enable others to make and use the same, reference being had to the accompanying drawings, forming a part of this specification.

The object of this invention is to provide a device that will promote combustion in boiler and other furnaces and prevent the escape of 15 smoke into the atmosphere by consuming the same before it passes into the stack or chimney, as will be hereinafter set forth.

This invention relates to an improvement on the particular appliance set forth in a former application filed May 28, 1889, Serial No. 20 312,428.

Figure 1 is a vertical longitudinal section of a boiler and furnace embodying our improved features; Fig. 2, a transverse section 25 in plane 2, Fig. 1, looking in the direction indicated by the arrow; and Fig. 3, a longitudinal section of one of the chambered heaters in plane 3, Fig. 2.

Referring to the drawings, A represents a 30 steam-boiler of the "marine" type; B, the fire-box; B', the grate-bars; C, the smoke-stack, and D D' the heaters or chambers in which the commingled steam and atmospheric air is received and heated preparatory to being 35 injected into the fire.

In a former application herein referred to but one air and steam heating chamber or pipe of a cylindrical form was shown. That particular construction and arrangement is 40 found to be better adapted for stationary and locomotive boilers. In the practical application of our improvement to "tug-boat" boilers it was found that the conditions were such, owing to the contracted dimensions of the 45 fire-box, that a different arrangement was required, which is provided for in the present application. Tug-boat boilers in some instances have the grate-bars on a level with the furnace-door, which arrangement would 50 not permit of the air and steam heating chamber being located transversely at the rear side

of the fire-box, for the reason that the flame would be blown out through the door-opening. It was also learned that "priming" of a tug-boat boiler was of frequent occurrence, 55 owing to the foul river-water, and that in consequence very moist steam would sometimes be sprayed into the furnace and the complete process of combustion greatly retarded. It was therefore found to be necessary to increase the heating-surface of the 60 heater, as will be hereinafter set forth.

In the present application two heaters are used, each having two chambers or compartments, and are located on each side of the 65 fire-box and lengthwise of the boiler. The heaters D D' are of an oval or double-elliptical form in cross-section, and have two chambers a a'. The rear side is perfectly flat, so as to lie closely to the inclosing sides of the 70 fire-box, while bolts inserted through the downwardly-projecting integral flange a² secure the heaters rigidly in place. This oval or flattened form is also necessary, as the heaters do not apparently take up as much 75 space in the fire-box or combustion-chamber as those of a cylindrical form would of the same capacity.

The horizontal partition b divides the heater or heaters into two chambers or compartments. This partition stops short of the opposite end of the heater from which the branch supply-pipes enter, leaving the opening b' and forming a communicating passage between the two chambers.

The upper parts of the heaters are provided 80 with a number of elongated apertures d, through which the superheated air and steam are injected into the furnace over the fire. These apertures open at different angles, as 85 shown in Fig. 2, so that a portion of the contents of the upper chamber is discharged across the fire in a horizontal plane and another portion in an upward direction, so as to thoroughly mingle with and consume all 90 of the carbon particles suspended in the smoke-gases. It will be observed that there are no apertures opening out from the lower chamber of the heaters, the lower chamber being intended for heating only and takes all 95 of the moisture out of the air and steam supply before it passes into the upper chamber 100

at the opposite end from which it entered, where it is still further heated before escaping into the fire, thus preventing any moisture from reaching the fire in case of priming. The supply-pipe E enters the boiler at the rear end and runs through the lower large flue F. The front end of the pipe E projects just far enough beyond the front end of the inclosing-flue to permit of the upper ends of the branch pipes a^3 a^4 being connected thereto. The branch pipes run off to each side of the furnace in a horizontal plane and then down to and are inserted in the respective back ends of the heaters D D'. In the rear projecting end of the pipe E is inserted the contracted end of the injector-nozzle G. A second nozzle H is inserted in the nozzle G, the inner end of which stops short of the tapering discharge end of the inclosing-nozzle. The interior outer end of the steam-nozzle is threaded, and the exterior part of the air-nozzle is correspondingly threaded, as at d', so as to be adjustable with reference to the outer nozzle, so that by turning the air-nozzle in or out the steam-passage d² between the two nozzles may be enlarged or diminished in regulating the volume of steam admitted with reference to the quantity of air passing in through the flaring open end g of the companion nozzle. The steam-pipe g² runs from the steam-dome of the boiler and has the terminal end inserted in the side of the steam-nozzle near its longitudinal center, as shown in Fig. 1. By this arrangement the volume of air and steam admitted can be conveniently regulated with relation to each other. A very small volume of steam is required in proportion to the air volume, as practical working has demonstrated. The construction and relative arrangement of the nozzles are such that the air-current is drawn in with great force, the air and steam being thoroughly mixed before reaching the heaters. The volume of air and steam is heated to a high degree in passing through the main heating-flue of the boiler into the heaters, where it is converted into an inflammable gas, which instantly ignites as it is injected into the fire, and thereby absorbs and consumes the smoke-gases given out from the fuel. The heaters might therefore be termed "gas-generators," as the mixed air and steam

is superheated to a high degree of temperature and of a very inflammable character and injected into the fire under considerable pressure, thus producing a very energetic 55 combustion. The steam and air may of course be taken in at each side of the boiler, injecting-nozzles being used for each heater.

The same arrangement of using two heaters, as herein shown, may be employed in 60 connection with a locomotive-boiler.

Having thus described our invention, what we claim as new, and desire to secure by Letters Patent, is—

1. In a smoke-consuming device, a heater 65 of an oval or elliptical form and divided into two chambers by a horizontal partition stopping short of one end of said heater, so as to provide a communicating passage between the chambers at the opposite end from which 70 the supply-pipe is inserted, and having a series of elongated discharge-apertures in one of said chambers, and a downwardly-projecting integral attaching-flange, substantially as described.

2. In a smoke-consuming device, the combination of the fire-box, the double-chambered heaters having discharge-apertures from one chamber only and arranged on each side of the fire-box, and the pipes for supplying a mixed volume of air and steam to said heaters, wherein the same is superheated and then injected into the fire, substantially as set forth.

3. In a smoke-consuming device, the combination of the fire-box, the heaters located at each side thereof, and of the construction substantially as described, the supply-pipe running longitudinally through the main flue of the boiler, the branch pipes connecting 90 said supply-pipe with the heaters, the combined air and steam injecting nozzles inserted in the outer end of the supply-pipe, and the steam-pipe connecting the steam-nozzle with the source of supply, substantially as and for the purpose set forth.

EBENEZER DANFORD.
CHARLES E. A. SAGLE.
